UNITED STATES PATENT OFFICE

WILLIAM PENN BRINTON, OF LANCASTER, PENNSYLVANIA, ASSIGNOR TO ARMSTRONG CORK COMPANY, OF LANCASTER, PENNSYLVANIA, A CORPORATION OF PENNSYLVANIA

APPARATUS FOR PRINTING

Application filed May 7, 1930. Serial No. 450,434.

This invention relates to apparatus for printing and is herein particularly described as applied to the manufacture of printed floor coverings.

5 In the printing of floor coverings by the well-known block-printing machine, the printing medium employed is a fluid paint which is supplied to blocks on the printing heads by means of a roll lying in a paint trough or color box, which color box is moved back and forth under the printing head between the downward printing movements thereof.

10 It is frequently desirable, where certain patterns are being printed, to provide on a single printing head a number of relatively movable printing blocks, which blocks may be separately employed for printing different parts of the design. Also, in certain cases 15 it may be desirable to print with two or more of the blocks together at one point of the design and to move one or more of such blocks to a non-printing position at another part of the design. A mechanism for doing 20 this is described and claimed in Patent No. 25 1,737,817 to Harry A. Webster, dated December 3, 1929.

When using sectional blocks difficulty is 30 some times encountered in that on occasion a line of demarcation between the various printing areas, as determined by different block sections, is noticeable. This is objectionable because it allows the base material to show through in a distinct line which some 35 times runs the entire length of the pattern. This is so because it is generally necessary to space the blocks apart slightly to permit reciprocation thereof independently of one another.

40 I have found that this difficulty can be overcome by brushing the wet color at the joining line. This brushing tends to blend the two printed areas together and to overcome the line on the product.

45 It is desirable that the brush bear against the material very lightly, as otherwise the brush tends to collect a pool of paint in front of it. In addition to this, heavy pressure by the brush results in the bristles of the brush 50 changing their angularity under certain con-

ditions, leaving concentrated bodies of paint on the face of the product. If the brush touches only very lightly, it is sufficient to cause blending or merging of the wet fluid paint forming the two printed areas but without any gathering together of the paint 55 into concentrated pools.

In a block printing machine the material moves forward in a step-by-step manner, but I have found that in certain cases, at least, 60 it is possible to so arrange the brush that at times there is no relative movement between it and the material, despite which fact it is possible to obtain the desired amount of brushing. In other cases it is important 65 that the brush always be in motion relative to the material, and this invention is the subject matter of the copending application of Fred G. Rottmund, Serial No. 442,140, filed April 7, 1930. 70

For the purposes of the present invention I have found that the brush or brushes employed may very well be carried by the color box. Preferably the brush is adjustably mounted on such color box so that the degree 75 of pressure with which it bears on the material may be closely adjusted. Despite the fact that the color box moves back and forth, it is possible, by properly adjusting the brush, to prevent the bristles thereof from "snapping" from one angular position to a reverse position and depositing pools of paint 80 on the material.

In the accompanying drawings, illustrating the present preferred embodiment of my 85 invention,

Figure 1 is a partial side elevation of a block printing machine showing two heads thereon and one color box with carrying brushes; 90

Figure 2 is a diagrammatic view illustrating sectional blocks such as may be employed on the printing heads of Figure 1;

Figure 3 is a top plan view of one of the color boxes having brushes applied thereto; 95

Figure 4 is a side elevation of one of the brushes; and

Figure 5 is a front elevation thereof.

The block printing machine illustrated in Figure 1 comprises a bed 2 over which the 100

fabric is moved in a step-by-step manner by pin bands 3, as is well known in the art. Guides 4 on the bed carry vertically reciprocable slides 5 on which the printing heads 6 are mounted. I have indicated in Figure 1 a part of the mechanism for actuating the sectional blocks as described in said Webster patent above referred to. The heads are reciprocated by cams 7 whereby the printing blocks, indicated in Figure 2 as 8a to 8f inclusive, are moved up and down to receive paint and print on the material going through the machine.

As described in Patent 1,737,817, above referred to, the sectional block actuating mechanism is such as to lower desired sections into paint receiving and printing position. As shown in Figure 2, a slight clearance is allowed between the blocks so as to permit of this movement.

Color boxes 9 of the usual type are employed, the several color boxes being connected by links 10 so that they may all be reciprocated in the usual fashion. The color box 9 runs on flanged wheels 11 having gear teeth 12 operating in racks 13 on the bed 2. As the color box is reciprocated the paint roll 14 is turned through gearing 15 making operative connection with the rack 13, so that a film of paint is laid over the printing surface of such blocks as are in lowered position when the color box passes under its printing head.

When the head 6 is lowered to print on the material, two adjacent blocks, for example, the blocks 8c and 8d, may be in printing position. They will apply the paint to the material but by reason of the clearance shown in Figure 2, there will be a clear line of division between the two printed areas. The two areas are merged or blended by means of brushes 16 carried on the color box 9. Each brush is secured by a bolt 17 to a bracket 18 whereby the vertical position of the brush may be adjusted. It will be understood that the paint employed is fluid in character and may therefore be blended together without the application of marked pressure by the brushes. It is preferred that the brushes touch the paint very lightly, thus insuring that the bristles will extend substantially perpendicularly at all times. This eliminates any tendency to brush away the paint and collect it into pools.

The invention has been specifically described as applied to the manufacture of floor coverings by a block printing machine wherein sectional heads are employed. It will be understood, however, that the invention in its broader aspects is not thus limited, but may be otherwise embodied or practiced within the scope of the following claims.

I claim:

1. In combination with a block printing machine having a movable paint carriage, a

brush attached to the paint carriage and adapted to engage the printed surface of the material.

2. In combination with a block printing machine having a movable paint carriage, a brush attached to the paint carriage and adapted to engage the printed surface of the material, the brush being adjustable.

3. In combination with a printing machine, means for printing over adjacent areas lying side by side and means effective only along the line of junction for brushing the printed areas so as to join the same.

4. In combination with a printing machine, means for supplying a wet paint or the like to adjacent areas, and means effective along the line of junction only for brushing the wet surface so as to join the areas.

In testimony whereof I have hereunto set my hand.

WILLIAM PENN BRINTON.
